UNITED STATES PATENT OFFICE.

ANDREW G. BRANDT, OF SCRANTON, PENNSYLVANIA.

FLEXIBLE FOLDING CUP.

977,159.

Specification of Letters Patent. Patented Nov. 29, 1910.

Application filed September 28, 1910. Serial No. 584,315.

To all whom it may concern:

Be it known that I, ANDREW G. BRANDT, a citizen of the United States, residing at Scranton, in the county of Lackawanna and 5 State of Pennsylvania, have invented a new and useful Flexible Folding Cup, of which the following is a specification.

It is the object of this invention to provide a collapsible drinking cup provided 10 with a movable bottom and with a keeper, the keeper and the bottom coöperating to maintain the collapsible body distended.

Another object of the invention is to provide 15 a cup of the character hereinbefore mentioned, with a slidable keeper, operating in a novel and improved manner to sustain and stiffen the cup.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed can be made within the scope of what is claimed without departing from the spirit of the invention.

In the drawings,—Figure 1 shows the invention in perspective, the cup being distended; Fig. 2 is a transverse section on the 30 line A—B of Fig. 1; Fig. 3 is a side elevation showing the cup folded; and Fig. 4 is a fragmental bottom plan.

The body 1 of the cup is cylindrical in 35 form, and is fashioned from resilient, yieldable material, such, for instance, as celluloid; although some other resilient, yieldable material might be employed to advantage. The body 1 is open at both ends, a strap 2, 40 provided at its lower end with an eye 3, being secured to the inside of the body 1, adjacent the lower end thereof. This strap 2 serves to uphold pivotally, the bottom 4, this bottom 4 comprising, as shown in Fig. 45 2, a base 5, and an upstanding flange 6, the flange 6 being provided with a loop 7, adapted to be received in the eye 3 of the strap 2, whereby the bottom 4 will be pivotally held within the contour of the body 1. The 50 flange 6 fits closely within the body 1, and when the bottom 4 is downturned, at right angles to the side wall of the body, a water tight closure at the lower end of the body will be effected.

55 Owing to the fact that the bottom 4 is provided with the upstanding flange 6, the

upper edge of the flange 6 being pivotally connected with the strap 2, it will be seen that, although the bottom 4 may be freely tilted upwardly, within the contour of the 60 body 1, the bottom 4 cannot tilt downwardly, under the weight of the liquid which is within the cup. However, in order that the bottom 4 may be sustained securely, a stop 8 is secured to the inner face of the body 1, 65 preferably at a point diametrically opposite to the strap 2. As shown in Fig. 4, the ends of the stop are secured by rivets 9 or the like, to the body 1, the straight intermediate portion 10 of the stop being spaced apart 70 from the body 1, to receive the bottom 4.

A guide 11, preferably a strip of flat metal is secured to the outside of the body 1, longitudinally of the body. The upper end of the guide 11 may be secured by means of 75 a rivet 12, passing through the body 1, the lower end of the guide 11 being secured by means of a rivet 14, passing through the body 1 and through the strap 2.

A keeper, preferably taking the form of 80 a ring 15, is slidably mounted between the guide 11 and the body 1. This ring 15 incloses the body 1 adjacent the upper end of the body, as shown in Fig. 2, the ring 15 obviously coöperating with the bottom 4 in 85 maintaining the contour of the cup.

When the cup is distended, as shown in Fig. 2, the guide 11 lies closely along the body 1, as shown at 16, a seat 17 being fashioned in the guide 11, adjacent the upper 90 end thereof, to receive the ring 15. Thus, when the cup is in use, the ring 15 will be maintained in the position shown in Fig. 2. In order to fold up the cup, the ring 15 is slid downwardly in the direction of the 95 arrow C until the ring abuts against the lower end of the guide 11, adjacent the point 18. The ring 15 may then be swung pivotally in the direction of the arrow D, over the lower end of the body 1, and finally 100 disposed in the upstanding position shown in Fig. 3. The bottom 4 is then pushed in, whereupon the body 1 may be flattened out and laid in the pocket of a garment, or in a suitable case.

Having thus described the invention what is claimed is:—

1. A cup comprising a collapsible body; a bottom hinged to the body; and a keeper slidably and pivotally secured to the body 110 and adapted to embrace the outside of the body.

2. A cup comprising a collapsible body; a movable bottom effecting a closure of the body; a guide secured to the outside of the body longitudinally of the body; and a body
5 inclosing ring slidable between the guide and the body and adapted to be swung over the lower end of the body and to be slid to the top of the body.

In testimony that I claim the foregoing as my own, I have hereto affixed my signature in the presence of two witnesses.

ANDREW G. BRANDT.
